UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

MECHANISM FOR SUPPLYING FASTENINGS

Application filed April 18, 1929. Serial No. 356,207.

This invention relates to mechanism for supplying fastenings, and more particularly to mechanism having one or more raceways from which fastenings are delivered separately as required for use. The invention is herein illustrated as applied to a multiple raceway mechanism of a type commonly used for supplying tacks to the tack-driving instrumentalities of pulling-over or lasting machines, features of which are disclosed, for example, in United States Letters Patent No. 1,002,422, granted on September 5, 1911 upon an application of R. F. McFeely. It is to be understood, however, that in its more general aspects the invention is not limited in utility to mechanism of that particular type.

Mechanism of the type illustrated in the above-mentioned Letters Patent includes a separator movable to separate and deliver tacks from the lower ends of the inclined raceways, and an end block located at the lower ends of the raceways and provided with grooves to receive the separated tacks and deliver them into the tubes that lead to the driving instrumentalities. Mounted on the end block are plates which overlap the separator and the lower ends of the several raceways and are so formed and arranged as to provide supporting surfaces for the heads of the tacks at the lower end portions of the raceways in the same plane as the tack-supporting surfaces of the remainder of the raceways. There is also a cover which overlies the lower end portions of the raceways and portions of the above-mentioned plates and the separator, the cover being mounted for upward swinging movement to expose the lower ends of the raceways and to facilitate access to the separator.

In the use of mechanism of the above-mentioned character it sometimes happens that movement of the separator is obstructed because of displacement of one or more tacks from normal position, the presence of an abnormally shaped tack, or for some other reason, and in that case it is usually necessary to gain access to the lower ends of the raceways and sometimes also to remove the separator. To afford access to the lower ends

of the raceways, and also to permit removal of the separator if that is necessary, the end block is accordingly so mounted that it may be readily displaced or removed from operative position. If the separator is then removed, however, the tacks will slide out of the raceways unless there is means to prevent them from doing so. If they are thus permitted to escape from the raceways, some of them may fall among the operating parts of the machine, into the tubes that lead to the drivers, or upon the floor and thus cause trouble and annoyance, and this involves also more or less waste of tacks. To avoid such consequences in the use of mechanism of this general character, the present invention provides novel means for controlling the fastenings in a raceway or raceways in such manner as to prevent their escape or delivery under abnormal conditions as, for example, when the separator is removed. Conveniently, and in accordance with one of the features of the invention, there is provided means controlled by the raceway cover for preventing delivery of fastenings whenever the cover is displaced from its normal position. Since the operator will almost invariably lift the cover if there is any interference with the movement of the separator, there is thus afforded a substantial safeguard against escape or fastenings from the raceways if the separator is removed. In order, however, to insure such control of the fastenings, the cover in the construction shown is provided with a member which projects in front of the end block when the cover is in its normal position and thus prevents removal of the end block, and accordingly of the separator, unless the cover has been lifted. In the construction illustrated the means for preventing delivery of the fastenings from the raceways comprises a member positioned over the raceways beneath the cover and normally maintained in an idle position in a recess in the cover, this member being movable downwardly toward the raceways into position to control the fastenings in response to the lifting of the cover.

In a further important aspect the invention provides novel means for retracting the fas-

tenings from the lower end portion of a raceway or raceways, as well as for preventing their escape, under abnormal conditions. Such means is particularly advantageous in 5 an organization of the type illustrated, in which the removable end block, as above explained, carries means which provides supporting surfaces for the heads of tacks at the lower end portions of the raceways, since the 10 movement of the tacks away from the lower ends of the raceways facilitates the removal of such means and its subsequent replacement in operative position. For the purpose 15 in view, in the construction shown the member hereinabove described for preventing delivery of fastenings from the raceways is so mounted and controlled as to have a movement lengthwise of the raceways to retract the 20 rows of fastenings in addition to its movement downwardly toward the raceways, both these movements resulting from the lifting of the cover. More particularly, as herein 25 illustrated this member is pivotally mounted for movement toward and from the raceways 30 on a slide which is movable lengthwise of the raceways, and the lifting of the cover results in swinging the member downwardly into operative relation to the raceways and also 35 in movement of the slide to cause the member 40 to retract the rows of fastenings.

The different features of the invention, including various novel details of construction and combinations of parts, will now be more particularly described by reference to the 45 accompanying drawings and pointed out in the claims.

In the drawings,

Fig. 1 is a perspective view of tack-supplying mechanism constructed in accordance 50 with the present invention, portions of the structure being broken away;

Fig. 2 is a vertical section in a plane parallel to the raceways, showing the parts as they appear in their normal operating positions;

Fig. 3 is a view similar to Fig. 2, illustrating the positions of the parts when the raceway cover is lifted and the tacks are retracted from the lower ends of the raceways; and

Fig. 4 shows detached a portion of the 55 mechanism for preventing delivery of tacks from the raceways and for holding them in retracted positions.

Since the general characteristics of mechanism of the type illustrated are well known 60 and are described in various prior Letters Patent including those hereinbefore mentioned, a brief reference thereto is all that is necessary for an understanding of the present invention. A rotary tack hopper 10 acts by intermittent movement to supply tacks to a plurality of inclined raceways 12 comprising members spaced apart to provide grooves or slots in which the tacks arrange themselves in rows supported by their heads. 65 Mounted to reciprocate across the lower ends

of the raceways is a tack separator 14 which separates the lowermost tacks from the raceways and delivers them into tubes 16 which lead to the tack-driving instrumentalities, these tubes being mounted in a raceway support 18. The separator 14 is detachably secured at its ends by screws 20 to a slide 22 by which it is operated. Mounted in front of the lower ends of the raceways is an end block 24 which serves, in part, as a guide 70 for the separator 14 and is provided with grooves 26 to receive the tacks delivered by the separator and to direct them into the tubes 16. Secured to the end block 24 are plates 28 which overlap the separator 14 75 and the lower ends of the raceways 12, portions of these plates being reduced in thickness and provided with slots in line with the raceway slots, as indicated at 30 (Figs. 2 and 3), to receive the tacks and provide supporting surfaces for the tack heads at the lower end portions of the raceways near the separator. The lower end portions of the raceways are recessed to receive these plates, so 80 that the surfaces of the plates that support the heads of the tacks are in the same plane as the tack-supporting surfaces of the remainder of the raceways.

Mounted in a fixed position over the upper 85 end portions of the raceways 12 is a cover plate 32, and pivoted at 33 on upraised portions 34 of this cover plate are arms 35 that project from a cover 36 which in its normal position (Figs. 1 and 2) is over the lower end 90 portions of the raceways, and also partially overlaps the plates 28 over the separator 14, the cover 36 carrying screws 39 the ends of 95 which normally rest on the plates 28 to assist in supporting it. This cover may be 100 swung upwardly about the pivot 33 to expose the lower end portions of the raceways.

In the use of mechanism of this character it sometimes happens that because of the presence of an abnormally shaped tack, displacement of one or more of the tacks from 110 normal position, or for some other reason movement of the separator 14 is obstructed. In that event it is usually necessary to gain access to the lower ends of the raceways and sometimes also to remove the separator in 115 order to get rid of the obstruction. Accordingly, as disclosed in the Letters Patent mentioned, the end block 24, with its plates 120 28 that overlap the separator, is so mounted that it may be readily removed, thus affording access below the separator to the lower ends of the raceways and also facilitating removal of the separator if that is necessary. To permit such removal the end block is provided at each of its opposite ends with 125 a spring-controlled plunger 38 (Fig. 1) which projects normally into a hole 40 in the raceway support 18. Members 42 which are mounted on pins 43 connected to the plungers 38 through slots in the block 24 provide means 130

whereby the plungers may be readily withdrawn from the holes 40 to release the block, and the block may then be removed by sliding it forwardly away from the ends of the raceways in a direction parallel to the incline of the raceways. The separator 14 is made up of a number of separate parts, as heretofore, secured together by screws and nuts indicated at 44 (Figs. 2 and 3) which are normally movable in a recess 45 extending lengthwise of the end block 24. In order to prevent these screws and nuts from interfering with the removal of the end block, the latter is provided with recesses indicated by dotted lines at 46 in Figs. 2 and 3, which are so arranged as to be opposite the screws and nuts 44 when the separator is in one position so that unobstructed removal of the end block is permitted.

It will be evident that if the separator 14 is removed the tacks will escape from the raceways unless means is provided to prevent them from doing so. The present invention provides novel means for preventing such delivery or escape of tacks, this means being constructed also to slide the rows of tacks upwardly away from the lower end portions of the raceways, and especially from the recessed portions of the plates 28 which, as hereinbefore described, support the heads of the tacks at the lower ends of the raceways, thus facilitating removal of these plates with the end block 24 and their subsequent replacement. For the purpose in view there is positioned under the cover 36 a bar 47 which extends over the series of raceways and is provided with a plurality of projections or fingers 48, one for each raceway, which are arranged to enter the grooves of the raceways in front of the lowermost tacks positioned therein. The bar 47 is supported on arms 49 which are pivotally mounted at 50 on a slide 52 provided on its opposite sides with tongues 54 which are mounted in grooves or slideways 56 formed in the upraised portions 34 of the fixed cover plate 32, these slideways extending in parallel relation to the raceways 12. The arms 49 at their rear ends are joined by a yoke-shaped member 60, and between this member and the slide 52 is a spring 62 which acts normally to hold the bar 47 upraised within an arched recess 64 (Fig. 3) in the cover 36, the arms 49 being positioned in recesses 66 in the cover. When the parts are in normal positions the projections 48 on the bar 47 are thus raised above the raceways and above the plates 28, as illustrated in Fig. 2.

In order to stop delivery of tacks from the raceways and to retract the rows of tacks from the lower ends of the raceways as hereinbefore described, the arms 49 are operated by the lifting of the cover 36 to swing the bar 47 downwardly, and by the same movement of the cover the slide 52 is operated

to carry the bar along the raceways, so that the projections 48 enter the grooves of the raceways and force the rows of tacks away from the lower ends of the raceways. For imparting the downward swinging movement to the arms 49 the arms 35 of the cover 36 are provided on their rear ends with cam faces 68 (Fig. 3) which act to depress the arms 49 when the cover is lifted, and for moving the slide 52 along the raceways by the same movement of the cover the latter is connected to the slide by a link 70 pivoted at 72 to the cover and at 74 to the slide. It will be understood, therefore, that as the cover 36 is swung upwardly about its pivot 33 it acts to swing the bar 47 downwardly toward the raceways and also to move it along the raceways through movement imparted to the slide 52, so that the projections 48 of the bar 47 are carried downwardly into the grooves of the raceways in front of the lowermost tacks through the slots 30 in the plates 28, and that by continued upward swinging movement of the cover the projections 48 are then moved along the raceways to retract the rows of tacks from the tack-supporting portions of the plates 28. Preferably, the projections 48 are so formed, as illustrated, as to extend rearwardly under the heads of the lowermost tacks into engagement with the shanks of the tacks, for better control of the tacks as they are moved upwardly along the raceways. To assist in maintaining the cover 36 in its lifted position, there are mounted in the upraised portions 34 of the plate 32 spring-controlled plungers 76 which are arranged to engage flat faces 78 on the rear end portions of the arms 35 of the cover. These plungers also assist in maintaining the cover in its normal downturned position by engagement with other flat faces 80 provided on the ends of the arms 35.

Since the operator will normally lift the cover 36 if there is any interference with the movement of the separator, it will be evident that by controlling through movement of the cover the means for preventing delivery of tacks from the raceways and for retracting them from the lower ends of the raceways, substantial certainty is afforded that this means will be in operative position at any time when the separator is removed. There is, however, further provided means for positively insuring that the tacks will be controlled in the manner desired, comprising a retaining member or projection 82 which is carried by the cover 36 and is arranged to project in front of the end block 24 when the cover is in its normal position, so that the end block cannot be removed and, accordingly, access to the separator and to the lower ends of the raceways cannot be obtained unless the cover has been lifted. It will be seen that the member 82 lies normally in the path of displacement of the

end block 24, that is, the path which the end block must take if it is removed from operative position, and in another aspect of the invention there is thus provided means which is controlled by movement of the retaining member 82 for preventing delivery of fastenings from the raceways if the end block is displaced.

The operation of the mechanism disclosed 10 will be understood from the foregoing description. If there is any obstruction to the movement of the separator 14, the operator lifts the cover 36, and by that movement of the cover the several rows of tacks are retracted by the bar 47 and its projections 48 from the lower end portions of the raceways where the tack-supporting portions of the plates 28 are located, and by the projections 48 escape of the tacks from the raceways is 15 prevented in case the operator finds it necessary to remove the end block 24 and the separator. The retractive movement of the tacks from the plates 28 permits these plates to be readily removed and replaced with the 20 end block. When the cover 36 is swung downwardly again by the operator, the tack-controlling mechanism described is returned to its starting position in response to such movement of the cover, thus permitting the 25 rows of tacks to slide downwardly again over the plates 28 as far as permitted by the separator 14.

While the invention is herein illustrated as applied to mechanism especially designed for 30 supplying tacks, the invention is not thus limited in utility, and in the appended claims the term "fastenings" is accordingly used in a generic sense to include articles of various forms in the control of which the invention 35 may be usefully employed.

Having described the invention, what I claim as new and desire to secure by Letters Patent of the United States is:—

1. In mechanism of the class described, a 40 plurality of inclined raceways for fastenings, a removable separator at the lower ends of said raceways, a cover over the raceways arranged to be moved from its normal position to facilitate removal of the separator, and means controlled by said cover for preventing delivery of fastenings from the raceways when the separator is removed.

2. In mechanism of the class described, a 45 plurality of inclined raceways for fastenings, a removable separator at the lower ends of said raceways, an end lock removable to afford access to the separator and the ends of the raceways, a cover over the raceways arranged to be moved from its normal position 50 to facilitate access to the separator, and means movable into operative position in response to the movement of said cover for preventing delivery of the fastenings from the raceways when the end block and separator are removed.

3. In mechanism of the class described, a plurality of raceways for fastenings, a cover over said raceways arranged to be displaced from its normal position, and means controlled by said cover for preventing delivery of fastenings from the raceways when the cover is displaced.

4. In mechanism of the class described, a plurality of raceways for fastenings, a cover over said raceways mounted for swinging movement to expose the raceways, and means movable into operative position in response to the swinging movement of said cover for preventing delivery of fastenings from the raceways.

5. In mechanism of the class described, a plurality of raceways, a cover over said raceways mounted for movement from its normal position, and means operative in response to such movement of the cover to close the raceways.

6. In mechanism of the class described, a plurality of inclined raceways for rows of fastenings, a cover over said raceways mounted for movement from its normal position, and means operative in response to such movement of the cover to move the rows of fastenings upwardly from the lower ends of the raceways.

7. In mechanism of the class described, a plurality of raceways for fastenings, a cover over said raceways mounted for swinging movement from its normal position, a device movable into position to prevent delivery of fastenings from the raceways, and cam means operated by the swinging of said cover to move said device into that position.

8. In mechanism of the class described, a plurality of raceways for fastenings, a cover over said raceways mounted for movement from its normal position, a device movable into or out of position to prevent delivery of fastenings from the raceways, spring means for normally holding said device in idle position, and means operated by the movement of said cover to move said device into operative position.

9. In mechanism of the class described, a plurality of raceways for fastenings, a cover over said raceways mounted for movement from its normal position, said cover having a recess on the side next to the raceways, a device movable into or out of position to prevent delivery of fastenings from the raceways, means for normally holding said device in an idle position in said recess of the cover, and means operative in response to movement of the cover from its normal position to move said device into operative position.

10. In mechanism of the class described, a plurality of raceways for fastenings, a cover over said raceways mounted for swinging movement upwardly from its normal position, said cover having a recess therein extending across the raceways on the side of the

cover next to the raceways, a bar extending across the raceways and movable into or out of position to prevent delivery of fastenings from the raceways, means for normally holding said bar uplifted in said recess of the cover to permit delivery of fastenings, and means operative in response to the upward swinging movement of the cover to move said bar into operative position.

11. In mechanism of the class described, a plurality of inclined raceways for supporting rows of fastenings, a cover over said raceways mounted for movement from its normal position, and a device for preventing delivery of fastenings from the raceways when the cover is displaced from its normal position, said device being movable into operative relation to the raceways and then lengthwise of the raceways to move the rows of fastenings upwardly from the lower ends of the raceways in response to movement of the cover.

12. In mechanism of the class described, a plurality of inclined raceways for supporting rows of fastenings, a cover over said raceways mounted for swinging movement upwardly from its normal position, a device over the raceways for preventing delivery of fastenings from said raceways when the cover is lifted, and means operative in response to the lifting of the cover to swing said device downwardly toward the raceways and to move it bodily lengthwise of the raceways to retract the rows of fastenings from the lower ends of the raceways.

13. In mechanism of the class described, a plurality of inclined raceways for supporting rows of fastenings, a cover over said raceways mounted for swinging movement upwardly from its normal position, a device over the raceways for preventing delivery of fastenings from the raceways when the cover is lifted, a slide movable lengthwise of the raceways on which said device is mounted for swinging movement toward or from the raceways, and means operative in response to the lifting of said cover to swing said device downwardly toward the raceways and to impart to said slide movement to cause the device to retract the rows of fastenings from the lower ends of the raceways.

14. In mechanism of the class described, a plurality of inclined raceways for supporting rows of fastenings, a cover over said raceways mounted for swinging movement upwardly from its normal position, a device over the raceways for preventing delivery of fastenings from the raceways when the cover is lifted, a slide movable lengthwise of the raceways on which said device is mounted for swinging movement toward or from the raceways, spring means for holding said device in idle position when the cover is in operative position, means operative in response to the upward movement of the cover to swing said device downwardly toward the raceways, and

a link connecting said cover and slide for operating said slide by the upward movement of the cover to cause said device to retract the rows of fastenings from the lower ends of the raceways.

15. In mechanism of the class described, a plurality of inclined raceways for supporting rows of fastenings, a device displaceable to afford access to the lower ends of said raceways, said device having thereon means constructed and arranged to provide supporting surfaces for the fastenings at the lower end portions of the raceways, a cover over the raceways mounted for movement from its normal position, and mechanism operative in response to such movement of the cover to move the rows of fastenings upwardly away from said supporting surfaces and to hold them in those positions.

16. In mechanism of the class described, a plurality of inclined raceways for supporting rows of fastenings, a separator at the lower ends of said raceways, an end block removable to afford access to said separator, said end block having thereon means constructed and arranged to provide supporting surfaces for the fastenings at the lower end portions of the raceways, a cover over the raceways mounted for movement from its normal position, and mechanism operative in response to such movement of the cover to move the rows of fastenings upwardly away from said supporting surfaces and to hold them in those positions during the removal of the end block.

17. In mechanism of the class described, a plurality of inclined raceways for fastenings, a device displaceable to afford access to the lower ends of said raceways, a cover over the raceways movable into or out of operative position, means controlled by said cover for preventing displacement of said device when the cover is in operative position and for permitting such displacement when the cover is in inoperative position, and means also controlled by the cover for preventing delivery of fastenings from the raceways when said device is displaced.

18. In mechanism of the class described, a plurality of inclined raceways for fastenings, a device displaceable to afford access to the lower ends of said raceways, a cover over the raceways arranged to be lifted from its normal position, means carried by said cover for preventing displacement of said device when the cover is in its normal position and for permitting such displacement when the cover is lifted, and mechanism operative in response to the lifting of the cover to prevent delivery of fastenings from the raceways when said device is displaced.

19. In mechanism of the class described, a plurality of inclined raceways, a device displaceable to afford access to the lower ends of said raceways, a cover over the raceways ar-

- ranged to be lifted from its normal position, a retaining member carried by said cover and arranged normally to prevent displacement of said device but to permit such displacement when the cover is lifted, and mechanism operative in response to the lifting of the cover to close the raceways.
20. In mechanism of the class described, a plurality of inclined raceways for supporting 10 rows of fastenings, a device displaceable to afford access to the lower ends of said raceways, a cover over the raceways arranged to be lifted from its normal position, a retaining member carried by said cover and arranged normally to prevent displacement of said device but to permit such displacement when the cover is lifted, and mechanism operative in response to the lifting of the cover to move the rows of fastenings upwardly 15 20 away from the lower ends of the raceways and to hold them in those positions.
21. In mechanism of the class described, a plurality of inclined raceways for fastenings, a device displaceable to afford access 25 to the lower ends of said raceways, a member arranged to lie normally in the path of displacement of said device but movable out of said path to permit such displacement, and means controlled by the movement of said 30 member for preventing delivery of fastenings from the raceways when said device is displaced.
22. In mechanism of the class described, a plurality of inclined raceways for fastenings, 35 a removable separator at the lower ends of said raceways, an end block removable to afford access to said separator, a member arranged normally to project in front of said end block to prevent its removal but to be 40 displaced to permit such removal, and means controlled by the displacement of said member for preventing delivery of fastenings from the raceways if said end block and separator are removed.
- 45 23. In mechanism of the class described, a plurality of inclined raceways, a device displaceable to afford access to the lower ends of said raceways, a retaining member arranged normally to lie in the path of displacement of said device but movable out of said path to permit such displacement, and mechanism operative in response to such movement of the retaining member to close the raceways.
- 50 24. In mechanism of the class described, a plurality of raceways for fastenings, a cover over said raceways displaceable from its normal position, and means for insuring against delivery of fastenings from the raceways 55 whenever said cover is displaced.
25. In mechanism of the class described, a plurality of raceways for fastenings having grooves to receive portions of the fastenings, a cover over said raceways displaceable from its normal position, members movable into 60 the grooves of the raceways to close them, and means for insuring that said members will be positioned in the grooves of the raceways whenever said cover is displaced.
26. In mechanism of the class described, a plurality of raceways for fastenings, a cover over said raceways displaceable from its normal position, and a member extending over the several raceways below said cover for preventing delivery of fastenings from the raceways when the cover is displaced.
27. In mechanism of the class described, a plurality of raceways for fastenings having grooves to receive portions of the fastenings, a cover over said raceways displaceable from its normal position, and a member extending over the several raceways below said cover for preventing delivery of fastenings from the raceways when the cover is displaced, said member having thereon a plurality of projections arranged to enter the grooves of the raceways to close them.
28. In mechanism of the class described, a plurality of raceways for fastenings, a cover over said raceways displaceable from its normal position, said cover having a recess therein on the side next to the raceways, and means normally maintained in an idle position in said recess but movable into position to prevent delivery of fastenings from the raceways if the cover is lifted.
29. In mechanism of the class described, a plurality of raceways for fastenings, a cover over said raceways displaceable from its normal position, and means positioned below said cover and movable downwardly into position to close the raceways if the cover is displaced.
30. In mechanism of the class described, a plurality of raceways for fastenings, a cover over said raceways displaceable from its normal position, and means for retracting the rows of fastenings from the lower ends of the raceways and for maintaining them in retracted positions if the cover is displaced.
31. In mechanism of the class described, a plurality of raceways for fastenings, a cover over said raceways, and controlling means located over the raceways below said cover and movable into or out of position to prevent delivery of fastenings from the raceways.
32. In mechanism of the class described, a plurality of inclined raceways for supporting rows of fastenings, a cover over said raceways, and means normally positioned below said cover movable to retract the rows of fastenings from the lower ends of the raceways.
33. In mechanism of the class described, a plurality of inclined raceways for supporting rows of fastenings, and a device movable into or out of position to prevent delivery of fastenings from said raceways, said device being mounted for movement in a direction trans-

verse to the length of the raceways to position it in operative relation to the rows of fastenings and for rectilinear movement lengthwise of the raceways to retract the rows of fastenings from the lower ends of the raceways.

34. In mechanism of the class described, a plurality of inclined raceways for supporting rows of fastenings, said raceways having grooves to receive portions of the fastenings, and a device movable into or out of position to prevent delivery of fastenings from said raceways, said device comprising a plurality of members mounted for movement as a unit into the grooves of the several raceways and for rectilinear movement lengthwise of the raceways to retract the rows of fastenings from the lower ends of the raceways.

35. In mechanism of the class described, a plurality of inclined raceways for supporting rows of fastenings, and a device over said raceways movable into or out of position to prevent delivery of fastenings from the raceways, said device being mounted for swinging movement downwardly toward the raceways and for bodily movement to retract the rows of fastenings from the lower ends of the raceways.

36. In mechanism of the class described, a plurality of inclined raceways for supporting rows of fastenings, a device over said raceways movable into or out of position to prevent delivery of fastenings from the raceways, a slide movable lengthwise of the raceways and on which said device is mounted for downward movement toward the raceways, and means for imparting to the device said downward movement and for also moving the slide to cause the device to retract the rows of fastenings from the lower ends of the raceways.

37. In mechanism of the class described, a plurality of inclined raceways for supporting rows of fastenings, a device over said raceways movable into or out of position to prevent delivery of fastenings from the raceways, a slide movable lengthwise of the raceways and on which said device is mounted for downward swinging movement toward the raceways, and a member operative to swing said device toward the raceways and also to impart to said slide movement to cause said device to retract the rows of fastenings from the lower ends of the raceways.

38. In mechanism of the class described, a plurality of inclined raceways for supporting rows of fastenings, a device over said raceways movable into or out of position to prevent delivery of fastenings from the raceways, a slide movable lengthwise of the raceways and on which said device is mounted for downward swinging movement toward the raceways, spring means for normally holding said device in upraised position, an

operating member mounted for swinging movement, cam means operated by said member for swinging said device downwardly toward the raceways, and a connection between said member and slide for imparting to the slide movement to cause said device to retract the rows of fastenings from the lower ends of the raceways.

39. In mechanism of the class described, a plurality of raceways for fastenings, means for separating and delivering fastenings from the lower ends of the raceways, and a bar extending across the raceways and movable either downwardly into position to prevent delivery of fastenings from the raceways or upwardly into position to permit delivery of fastenings.

40. In mechanism of the class described, a plurality of raceways for fastenings having grooves to receive portions of the fastenings, means for separating and delivering fastenings from the lower ends of the raceways, and a bar extending across the raceways and movable either downwardly into position to close the raceways or upwardly into position to open the raceways, said bar having thereon a plurality of projections arranged to extend into the grooves of the raceways when the bar is in its lowered position.

41. In mechanism of the class described, a plurality of inclined raceways for supporting rows of fastenings, said raceways having grooves to receive portions of the fastenings, a bar extending across the raceways and movable either downwardly into position to prevent delivery of fastenings from the raceways or upwardly to permit delivery of fastenings, said bar having thereon a plurality of projections arranged to extend into the grooves of the raceways when the bar is in its lowered position, and means for moving said bar downwardly and for also moving it lengthwise of the raceways to retract the rows of fastenings from the lower ends of the raceways.

42. In mechanism of the class described, a raceway for fastenings, a cover over said raceway mounted for upward movement out of its normal position about an axis extending widthwise of the raceway, and means movable into operative position in response to said movement of the cover for preventing delivery of fastenings from the raceway.

43. In mechanism of the class described, a raceway for fastenings having a groove to receive portions of the fastenings, a cover over said raceway mounted for movement out of its normal position, and a raceway-closing device movable into the groove of the raceway in response to said movement of the cover to prevent delivery of the fastenings from the raceway.

44. In mechanism of the class described, an inclined raceway for supporting a row of fastenings, a cover for said raceway mount-

ed for movement out of its normal position, and means operative in response to said movement of the cover to retract the row of fastenings from the lower end of the raceway and to hold them in retracted position.

45. In mechanism of the class described, an inclined raceway for fastenings, a device displaceable to afford access to the lower end of said raceway, a retaining member arranged normally to lie in the path of displacement of said device but movable to permit such displacement, and means arranged to be rendered operative in response to such movement of the retaining member to prevent delivery of fastenings from the raceway when said device is displaced.

46. In mechanism of the class described, an inclined raceway for fastenings, a device displaceable to afford access to the lower end 20 of said raceway, a retaining member arranged normally to lie in the path of displacement of said device but movable to permit such displacement, and a raceway-closing member movable to operative position in response to such movement of the retaining member.

47. In mechanism of the class described, an inclined raceway for supporting a row of fastenings, and a device movable into or out 30 of position to prevent delivery of fastenings from the raceway comprising a member mounted for downward movement toward the row of fastenings and for movement then in a rectilinear path to retract the row of fastenings from the lower end of the raceway.

48. In mechanism of the class described, an inclined raceway for supporting a row of fastenings, said raceway having a groove to 40 receive portions of the fastenings, and a device over the raceway movable into or out of position to close the raceway, said device comprising a member mounted for downward swinging movement into the groove of the raceway and for rectilinear movement to retract the row of fastenings from the lower end of the raceway.

49. In mechanism of the class described, an inclined raceway for supporting a row of 50 fastenings, a slide movable lengthwise of the raceway, a member mounted on said slide to swing relatively to the slide toward or from the raceway, and means for swinging said member toward the raceway and for then imparting to the slide movement to cause said member to retract the row of fastenings from the lower end of the raceway.

50. In mechanism of the class described, an inclined raceway for supporting a row of 60 fastenings, a slide movable lengthwise of the raceway, a member mounted on said slide to move relatively to the slide toward or from the raceway, and a device operative by movement in one direction to move said member toward the raceway and also to impart to

said slide movement to cause said member to retract the row of fastenings from the lower end of the raceway.

51. In mechanism of the class described, an inclined raceway for supporting a row of 70 fastenings, said raceway having a groove to receive portions of the fastenings, a slide movable lengthwise of the raceway, a raceway-closing member mounted on said slide to move relatively to the slide into or out of the groove 75 of the raceway, and an operating member arranged to control both said raceway-closing member and slide to cause the closing of the raceway and retractive movement of the row of fastenings from the lower end of the 80 raceway.

52. In mechanism of the class described, a plurality of raceways for fastenings, a cover over said raceways displaceable from its normal position, and means movable relatively to said cover but controlled thereby for preventing delivery of fastenings from the raceways when the cover is displaced.

53. In mechanism of the class described, a plurality of raceways for fastenings, a cover 90 over said raceways mounted for upward swinging movement about an axis extending widthwise of the raceways, and means controlled by said cover for preventing delivery of fastenings from the raceways when the 95 cover is swung upwardly.

54. In mechanism of the class described, a plurality of raceways for fastenings, a movable cover over said raceways, means movable into and out of position to prevent delivery 100 of fastenings from the raceways, and cam means operated by said cover for controlling said movable means.

55. In mechanism of the class described, a plurality of raceways for fastenings, a movable cover over said raceways, controlling means for the fastenings movable to different positions respectively for preventing or permitting delivery of fastenings from the raceways, spring means for moving said controlling means to one position, and means operated by the cover for moving the controlling means to its other position.

In testimony whereof I have signed my name to this specification.

BERNHARDT JORGENSEN.
